6 Claims. (Cl. 1—32)

1

This invention relates to devices for securing heels from the counter-portion of shoes or the like by nails or equivalent fastening means which are inserted in tubes or grooves set obliquely with respect to the bottom of the counter-portion of the shoe and are driven in by drivers slideable in said tubes or grooves under the action of a common plunger.

There are two main requirements of such devices the fulfilling of which causes difficulties in designing, viz: the fastening means (mostly nails) should penetrate into the heel at a sufficient slope with respect to the bottom of the counter-portion of the shoe (up to 20°) from positions as near as possible to the outer circumference, and the shape of the driver-head should be adapted to the heel portion of the shoe as accurately as possible. The first condition concerning the slope of the fastening means is of great importance for ensuring firm attachment to the heel, particularly with high heels for ladies' shoes, whereas the second condition is important for properly positioning the shoe on the driver-head and contributes to the reliability of a perfect attachment of the heel as well as facilitating the work and thereby increasing the rate of output.

With known devices it has not been possible to fulfill both of the aforesaid requirements at the same time, the fulfilling of the one having been achieved at the expense of the other. For example, if one attempted to adapt the outer shape of the driver-head accurately to the shape of the heel portion of the shoe, it was necessary to give to the nails or other fastening means that were to be driven, lesser slope with respect to the bottom of the counter-portion of the shoe, and to drive them in at a greater distance from the heel profile.

The use of flexible or like deformable drivers guided in curved guides to overcome these disadvantages led to designs which showed many sources of breakdown in operation. Moreover, resilient drivers are subjected to alternating stresses which affect their length of life considerably.

However, there are known devices by which the fastening means are driven in at a sufficient slope with respect to the bottom of the counter-portion of the shoe and as near as possible to the edge of the heel, without the use of resilient drivers or other similar components; but with these devices either the drivers protrude in their initial position from the driver-head and make the correction positioning of the shoe on the

5 driver-head difficult, or the driver-head has to be appropriately enlarged in the upper portion of the shoe to be operated upon, giving up the natural shape of the heel portion of the shoe, in order to be capable of housing the drivers, if necessary. The said upper portion must be large enough to admit the driver-head.

10 For example, a device for securing heels by nailing from inside the counter-portion of the shoe has become known in which the drivers slide in obliquely disposed tubes and are equipped with projections guided in guide grooves of a common driver-head. An inherent disadvantage of this known device consists in the unfavorable distribution of the guides, particularly in the common driver-head, where jamming may easily occur which leads to breakages. The driver-head proper is much too high in this known arrangement and makes the adaptation to the shape of 15 the heel difficult, particularly in respect of the reduction towards the upper portion. These unfavorable conditions are caused particularly by the fact that the supporting wall of the driver-head in which the said tubes are housed possesses substantially a thickness corresponding to the length of these tubes, so that the free space required for the movement of the common driver-head has to be provided underneath the said thick wall whereby the necessary guide projections of the drivers must also be unfavorably long.

20 An object of the present invention is to remove the above mentioned drawbacks and deficiencies.

To this end the invention consists in that the guides in the common driver-plunger for the projections of the drivers lie at the beginning of the active stroke of the plunger, approximately at the bases, i. e., at the lower ends of the obliquely disposed tubes or grooves in which the drivers are guided, so that the said guides move 25 during the entire active stroke of the plunger along the said tubes or grooves and inside the space limited by these tubes or grooves, whereby the drivers themselves are completely and reliably guided and assume the correct slope and position with respect to the bottom of the counter-portion of the shoe, the outer shape of the driver-head being capable of being accurately adapted to the shape of the heel portion of 30 the shoe.

35 The foregoing and other features of the invention will become apparent from the description of one embodiment which will now be given by way of example and which is illustrated on 40 the accompanying drawing.

Figure 1 represents a longitudinal section of a driver-head according to this embodiment with the adjacent part of the shoe to be operated upon being indicated in dotted lines;

Fig. 2 represents a cross section through the driver-head with the driver-plunger in its initial position;

Fig. 3 shows a similar cross section but with the driver-plunger at the end of its driving stroke;

Fig. 4 is a sectional plan taken along the line 4-4 of Fig. 1, of one of the drivers with its tube or groove;

Fig. 5 is a sectional top plan view of the driver-head seen in accordance with Fig. 1;

Fig. 6 is a sectional plan of the driver-head taken along the lines 6-6 of Fig. 1; and

Fig. 7 is a sectional plan of the driver-head taken along the lines 7-7 of Fig. 1.

From Fig. 1 it will be seen that the driver-head is accurately adapted to the shape of a heel, and that it has also a reduction towards the upper portion 16 of the shoe to be operated upon; it consists of an upper part 1 and a lower part 2.

The upper part 1 is designated as a hollow body having an upper wall 17 integrally connected with depending lateral walls that contain the tubes 3 for the heel fastening means here shown as nails 4. The tubes 3 form tubular guides for nails in an oblique direction with respect to the upper wall 17 of the hollow body 1, each tube 3 being provided with a slot 5 which is open into the interior of the hollow body and through which slots protrude the lateral projections 6 of the drivers 7 which work in the tubes 3. These projections 6 are guided in transversely extending guide grooves 14 (see particularly Fig. 7) of the common driver-plunger 8, and the grooves are covered by a plate 9 attached to the plunger, for example by means of screws 10, as can be seen in Figs. 1-3 and 7. The said guide grooves 14 are disposed substantially in a transverse plane extending through the bases of said tubular guides 3 when the plunger 8 is at the beginning of its driving stroke (see particularly Fig. 2). The plunger is guided in the lower part 2 of the driver-head and is operated through any known driving device. The upper part 1 of the head is attached to the lower part 2 by means of screw bolts 11 and 12; it carries an adjustable support 13 of known kind for supporting the toe portion of the shoe that is to be operated on.

With the illustrated embodiment nine nails can be driven simultaneously. However, since not all of the guide grooves 14 required for the lateral projections of nine drivers can be accommodated in the upper wall of the plunger 8, two of the drivers 7', are extended downwards, so that their lateral projections 6' lie lower and are guided in grooves 15 in the plunger underneath the grooves 14.

In Figs. 1-3 the part of a shoe to be operated upon is indicated in dotted lines whereas 16 designates the hereinbefore mentioned upper portion of the shoe and 18 the heel to be secured.

It will be seen that the guidance of the drivers 7 and 7' by the projections 6 and 6', respectively, is a very favorable arrangement. As indicated in Figs. 1-3 each driver and its projection are combined in the shape of an oblique letter L, i.e. each driver and its projection form arms of an angle, the apex of which lies on the point of intersection of the axis of the retaining tube 3 and the axis of the respective guide grooves 14 or

15, respectively. The disposition of the cavity in which the common plunger 8 moves adjacent to the front of the depending lateral wall at 17a that integrally connects with the upper wall 17 permits the drivers 7 (i.e. all the drivers with the exception of the two denoted 7') to be designated very short whereby the guidance of the same by their lateral projections is made proof against jamming.

10 The manner of operation of the described device is as follows:

The nails 4 are inserted into the tubes 3 by means of a known device, the shoe 16, 18, to be treated is put on the driver-head, and the plunger 8 is pressed upwards from the position shown in Fig. 2 to that shown in Fig. 3, whereby the drivers 7, 7' are guided obliquely upwards in the tubes 3 and drive the nails through the bottom of the counterportion of the shoe into the heel 18, the lateral projections 6, 6' of the drivers sliding inwards in the guide grooves 14, 15 towards the center of the plunger. After the nailing operation the plunger 8 returns again, for example under the action of a spring not shown, together with the drivers 7 and 7' to the initial position shown in Fig. 2.

While I have described my invention in one of its preferred embodiments I realize that modifications may be made and I desire that it be understood that no limitations upon my invention are intended other than may be imposed by the scope of the appended claims.

I claim:

1. In a device for securing the heels of footwear by fastening means such as nails driven into the heel from the interior of the footwear, the combination of a hollow body shaped for reception of the counter-portion of the footwear, said hollow body having a cavity therein terminating in depending lateral side walls and a depending front end wall, tubular guides for the fastening means extending in the body obliquely with respect to the front end wall of the cavity, said tubular guides having longitudinally extending slots 35 therein opening into the interior of the hollow body, drivers slidable in the tubular guides, lateral projections on the drivers extending through the slots in said tubular guides, and an operating plunger common to said drivers the lateral projections 40 on said drivers being disposed in transverse planes extending through the bases of the slots in said tubular guides when the plunger is at the beginning of a driving stroke, said drivers being confined in linear paths through said tubular guides by coacting guide grooves in said plunger during an entire driving stroke of the plunger.

2. A device for securing the heels of footwear by fastening means such as nails driven into the heel from the interior of the footwear as set forth in claim 1 in which each of said lateral projections form with its associated driver the shape of an obliquely arranged letter L the apex of the angle of which lies in the point of intersection 60 of the axes of the tubular guides and the axis of the respective guide grooves.

3. A device for securing the heels of footwear by fastening means such as nails driven into the heel from the interior of the footwear as set forth in claim 1 in which the front end wall of the cavity in the hollow body has a plane surface disposed at an oblique angle to the top of the cavity in the hollow body.

4. A device for securing the heels of footwear 75 by fastening means such as nails driven into the

heel from the interior of the footwear as set forth in claim 1 in which each of the lateral projections form with its associated driver the shape of an obliquely arranged letter L, the apex of the angle of which lies in the point of intersection of the axes of the tubular guides and the axis of the respective guide grooves, said lateral projections being held to the top of said plunger and movable in a vertical path to a position approaching the under side of the top of the hollow body.

5. A device for securing the heels of footwear by fastening means such as nails driven into the heel from the interior of the footwear as set forth in claim 1 in which the hollow body has the external lateral side surfaces thereof shaped to conform with the counter portion of the footwear and wherein the top surface of said hollow body serves as a support for the footwear.

6. A device for securing the heels of footwear by fastening means such as nails driven into the heel from the interior of the footwear as set forth in claim 1 in which each of said lateral projec-

tions form with its associated driver the shape of an obliquely arranged letter L the apex of the angle of which lies in the point of intersection of the axes of the tubular guides with the axis of the respective guide grooves, said lateral projections being held to the top of said plunger and movable in a vertical path to a position approaching the under side of the top of the hollow body.
